FIRE BOX OF OIL BURNING LOCOMOTIVES

Carl F. Gerlinger, Dallas, Oreg.

Application July 3, 1933, Serial No. 678,772

6 Claims. (Cl. 158—3)

The present arrangement of the fire box of oil burning locomotives is inefficient due to the fact that the fire box is not properly supplied with preheated air to insure complete combustion. As a consequence, several very undesirable results are caused, namely, accumulation of unburned oil around the damper doors and fire door; formation of carbon on the flash wall and side walls of the fire box; heavy black smoke; uneven fire, which causes flares, flames and black smoke to issue from the damper door and fire door endangering trainmen. These flares often blind the trainmen, making it difficult for them to board the train. Imperfect combustion further causes failure in valuable usage of the fuel oil, since part of it remains unburned.

I have discovered that said troubles may be avoided, and efficient combustion assured by so controlling the admission of air into the fire box that it becomes divided into two volumes in the ratio of approximately 3 to 1; admitting the larger volume into the fire box directly in front of the flash wall thereof, and the smaller volume at the front end of the fire box.

Furthermore, it is necessary that the air admitted into the fire box be preheated to a relatively high temperature, as a means of promoting complete combustion.

The object of my invention is primarily so to construct the lining of the fire box that the said control of the admission of air, the dividing of the same into said proportionate volumes, and the preheating of the air may be efficiently accomplished.

The admission of cold air into the fire box is frequently the cause of damage to flue, brick-work, sheets and staybolts of the locomotive.

I attain this object by providing the fire box lining with air passageways thru which the air admitted into the fire box must pass, which heat the air to the desired temperature.

A further object of my invention is to so arrange said lining that it may be introduced thru the openings now provided in standard fire boxes of the present locomotives. The latter object of my invention I attain by constructing the lining in the form of interfitting units. The lining units are provided with passageways, or ducts therethru, and are adapted to be so arranged within the fire box as to partition the front end thereof from the rear end; and the areas of the openings from said passageways into the interior of the firebox are such that the major part of the air is admitted directly in front of the flash wall in the rear section of the fire box;

which major part I found should be approximately 75% of the total volume of air which the fire box will hold, and the remaining 25% being admitted thru the opening from the passageways of the lining at the front section of the fire box.

I further preferably provide the hollows of the wall lining units with heat radiating fins, in order the better to transmit the heat from the hot wall linings of the fire box to the air passing thru said passageways of the walls.

Further details of construction of my fire box lining are hereinafter fully described with reference to the accompanying drawings.

In the drawings:

Fig. 1 shows a longitudinal vertical rear section 15 of a conventional locomotive and its fire box; the section being taken along the line 1—1 of Fig. 2, through the center of the fire box looking at the interior side wall with a portion of the wall broken away, and the location of the heat radiating fins 20 indicated partly in broken lines and partly in full lines;

Fig. 2 shows a transverse section along line 2—2 of Fig. 1, looking at the interior face of the front wall lining of the fire box, a portion of 25 which wall is broken away to illustrate the location of baffles;

Fig. 3 shows a plan section along line 3—3 of Fig. 2 thus looking down on the floor lining of the fire box;

Figs. 4a, 4b, and 4c show isometric fragments of the rear portion or section of my floor and wall linings of the fire box, looking from the rear toward the front end, and illustrating the arrangement of air passageways thru the lining units;

Figs. 5a and 5b show isometric fragments of the front portion or section of my fire box lining, looking from the front toward the rear, and illustrate the arrangement of the air passageways thru this portion;

Fig. 6 shows an isometric view of the units of my fire box as they are assembled in the ashpit of the fire box; the ashpit and the flash wall of the fire box being omitted;

Figs. 7 to 15, inclusive, show isometric views of 45 the floor lining units a to i, inclusive;

Fig. 16 shows an isometric view of the cover plate j for floor units h and i (shown by Figs. 14 and 15) when assembled;

Fig. 17 shows an isometric view of lower section 50 k of my front wall lining;

Fig. 18 shows an isometric view of the upper section m of said front wall lining; and

Figs. 19 to 28, inclusive, show isometric views 55 of said wall lining units n to w.

Referring to Figs. 1, which shows the rear portion of the boiler and the fire box of a locomotive, and Fig. 2 which shows a transverse section thru the fire box;

5 In the bottom of the ashpit 2 of the fire box are located the floor lining units *a* to *i*, inclusive, details of which are shown by Figs. 7 to 15, inclusive. The arrangement of these floor units as assembled within the ashpit of the fire box may be seen from Fig. 6. The units *b*, *d* and *f*, see Figs. 8, 10 and 12, have lateral ledges 3 adapted to form lap joints with the adjoining units *a*, *c*, *e*, *g*, shown by Figs. 7, 9, 11 and 13. The side wall lining units *n* to *w*, see Figs. 19 to 28, inclusive, assembled as shown in Fig. 6, form the left side wall lining of the fire box looking towards the front; and the side wall lining units *n'* to *w'*, see Fig. 6, form the right side wall lining of the fire box. The right side units are in construction the same as the left side units, being merely changed in form for placing on the right side.

10 The wall units *k*, see Fig. 17, and *m*, see Fig. 18, assembled as shown in Fig. 6, form the front wall lining of the fire box.

15 25 The side wall units *n* to *w* and *n'* to *w'* are provided with ledges 4 and 5 forming lap joints when said units are assembled together. The front wall section *k*, see Fig. 17, is provided with lip 21 which forms a lap joint when assembled with front wall section *m*, see Fig. 18.

30 35 The side wall units are provided with interior heat radiating fins 16, which assist in dissipating the heat from the side walls to the air passing thru them, thus preheating the air. The baffles 17, and 17', located in the front wall *m*, *k*, see Figs. 2 and 5a, serve the same purpose as the baffles 16. Flanges 18 on the floor units *a* to *i*, see Figs. 7 to 15, are provided to hold the side wall units in place. The flanges 19 on units *w* and *w'* (see Fig. 28) hold the wall units *k* and *m* (Figs. 17 and 18) in place.

40 45 50 The flanges 18 and 20 on the upper faces of floor units *a* to *g*, Figs. 7 to 13, constitute drip pans in which to catch unburned oil which may drop from the burner when starting the fire, thus preventing such oil from flowing between the sections into the lower passageway, where it would cause smoke, or flow out the damper doors. The oil so collected will later on, as the fire box gets heated, be consumed.

55 55 The plate *j*, Fig. 16, is placed within the flanges 18 and 20 of the floor units *h* and *i*, Figs. 14 and 15, also serves as a drip pan under the burner.

60 65 70 Air enters the fire box thru passageways 6, 6' of the bottom or floor units *a* to *g*, at the rear end, and thence is diverted by the end walls *g*² of the floor unit *g*, and passes into the spaces 9² thru openings 11 and 11' of the side wall units *u*, *t* and *u'*, *t'*. Said travel of the air is indicated by arrows in Fig. 1. The end walls *u*² then divert the air. Part of the air from the spaces 9² then passes thru the air passageways 9, 9', to the side wall units *p*, *p'*, through the openings 9³ into the spaces 13 and 13' of the side wall units.

75 75 Other portions of the air pass from the spaces 9² thru the upper spaces 9⁴ of the side wall units. The air passing thru said upper spaces 9⁴ also enters spaces 13 and 13' of the side wall units *p*, *q* and *p'*, *q'*. The units *p* to *t* inclusive and *p'*, *t'* inclusive are provided with heat radiating fins 16; a portion of the air passing thru the upper spaces 9⁴ of the side wall units *p* to *t* and *p'* to *t'* also passes into the side wall units *n*, *o* and *n'*, *o'* and from the latter also may enter the

opening 13. From said space 13 the air then enters the interior of the fire box. The air at the front end of the fire box is admitted thru openings 7, 7', see Figs. 5a and 5b.

5 The air enters thru passageways 7, 7' thru the front floor units *h* and *i*, Figs. 14 and 15, thence passes thru openings 12 and 12' into spaces 10, 10' of the front wall units *v*, *w* and *v'*, *w'*. From there, thru openings 14 and 14' of side wall units *w* and *w'*, the air enters space 22 of the horizontal front wall units *m* and *k*; see Figs. 5a, 5b, 10 17 and 18. Then the air passes thru the openings 15 and 15' over baffle plates 17', see Fig. 17, into the interior of the fire box.

15 The amount of air admitted through the openings 6 and 6' of the rear section and 7 and 7' of the front section can be controlled by adjustment of the dampers 8 and 8', respectively. I have found it desirable to have approximately 75% of all the air admitted to the fire box enter 20 the fire box at the rear, that is thru the spaces 13 and 13'. For this reason the rear passageways beginning at 6 and 6' and ending at 13 and 13' are considerably longer than the front passageways, beginning at 7 and 7' and ending at 25 15 and 15', to allow for the adequate heating of a greater volume of air.

30 The opening 2a, see Figs. 1, 2 and 5b, is for the insertion of the burner 2b, the latter indicated in Figs. 1 and 2. 32 shows portions of the side wall 30 of the boiler. 33 shows the flash wall built in the rear of the fire box.

35 The air in passing thru said passageways, its course being approximately indicated by the arrows in Fig. 1, becomes preheated to a high degree, and besides it is properly distributed with regard to the rear and front sections of the fire box so as to form a proper intermixture with the fuel oil spray and thus effect efficient combustion. No cold air whatever is admitted 40 into the fire box, which prevents injury from that source; and by admitting the air into the rear section of the fire box directly in front of the flash wall, the depositing of carbon on such wall is prevented. The illustrations of the drawings 45 are merely intended to illustrate one practical mode of carrying my invention into practice.

I claim:—

1. In an oil burning locomotive provided with a fire box, an oil burner located at the front 50 of said fire box, and a flash wall located at the rear of said fire box, a fire box composed of interfitting hollow units, providing air heating passageways discharging into the fire box, certain of said hollow units having closed ends 55 whereby the air passageways are separated into front and rear sections permitting the preheated air to enter the fire box at both the front and the rear ends simultaneously, the air passageways of the front sections having their outlets at the front of the fire box and the air passageways of the rear sections having their outlets close to the flash wall at the rear of the fire box.

2. In an oil burning locomotive provided with a fire box, an oil burner located at the front of said fire box, and a flash wall located at the rear of said fire box, a fire box lining composed of interfitting hollow units providing air heating passageways discharging into the fire box, certain of said hollow units having closed ends 70 whereby the air passageways are separated into front and rear sections permitting preheated air to enter the fire box at both the front and the rear ends simultaneously, a damper at the in- 75

take opening of each of said front and rear passageway sections to control the volume of air admitted through each section, the dampers of the front sections being adjustable independently of the dampers of the rear sections.

5. In an oil burning locomotive provided with a fire-box, an oil burner located at the front of said fire box, and a flash wall located at the rear of said fire box, a fire box lining composed of interfitting hollow units providing air heating passageways discharging into the fire box, certain of said hollow units having closed ends whereby the air passageways are separated into front and rear sections permitting the preheated air to enter the fire box at both the front and the rear ends simultaneously, the air passageways of the front sections having their outlets at the front of the fire box and the air passageways of the rear sections having their outlets close to the flash wall at the rear of the fire box, a damper at the intake opening of each of said front and rear passageway sections to control the volume of air admitted through each section, the dampers of the front sections being adjustable independently of the dampers of the rear sections.

4. In an oil burning locomotive provided with a fire box, an oil burner located at the front of said fire box, and a flash wall located at the rear of said fire box, a fire box lining composed of interfitting hollow units providing air heating passageways discharging into the fire box, certain of said hollow units having closed ends whereby the air passageways are separated into front and rear sections permitting the preheated air to enter the fire box at both the front and the rear ends simultaneously, said hollow units with the said closed ends being located so that the passageways of the rear sections will be longer than the passageways of the front sections.

5. In an oil burning locomotive provided with a fire box, an oil burner located at the front of

said fire box, and a flash wall located at the rear of said fire box, a fire box lining composed of interfitting hollow units providing air heating passageways discharging into the fire box, certain of said hollow units having closed ends whereby the air passageways are separated into front and rear sections permitting the preheated air to enter the fire box at both the front and the rear ends simultaneously, the air passageways of the front sections having their outlets 10 at the front of the fire box and the air passageways of the rear sections having their outlets close to the flash wall at the rear of the fire box, said hollow units with the said closed ends being located so that the passageways of the 15 rear sections will be longer than the passageways of the front sections.

6. In an oil burning locomotive provided with a fire box, an oil burner located at the front of said fire box, and a flash wall located at the 20 rear of said fire box, a fire box lining composed of interfitting hollow units providing air heating passageways discharging into the fire box, certain of said hollow units having closed ends whereby the air passageways are separated into 25 front and rear sections permitting the preheated air to enter the fire box at both the front and the rear ends simultaneously, the air passageways of the front sections having their outlets at the front of the fire box and the air passageways of the rear sections having their outlets close to the flash wall at the rear of the fire box, a damper at the intake opening of each of said front and rear passageway sections to control the volume of air admitted through each 30 section, the dampers of the front sections being adjustable independently of the dampers of the rear sections, said hollow units with the said closed ends being located so that the passageways of the rear sections will be longer than 35 the passageways of the front sections.

CARL F. GERLINGER.
